Primary Examiner — Joseph Kukella*Assistant Examiner* — Lavon M. Amerson(74) *Attorney, Agent, or Firm* — Carlson, Gaskey & Olds, P.C.(57) **CLAIM**

The ornamental design for a vehicle engine bay wash cover as shown and described.

DESCRIPTION

FIG. 1 is a rear-perspective view of an vehicle engine bay wash cover showing my new design in a condition of use. FIG. 2 is a top view of a cover, which is the left-hand cover in FIG. 1.

FIG. 3 is a bottom view of the cover.

FIG. 4 is a right side view of the cover.

FIG. 5 is a left side view of the cover.

FIG. 6 is a bottom-rear perspective view of the cover; and, FIG. 7 is a top-front perspective view of the cover. Broken lines in the drawings form no part of the claimed design.

1 Claim, 4 Drawing Sheets(56)
